(57) **CLAIM**

The ornamental design for a LED panel, as shown and described.

DESCRIPTION

FIG. 1 is a front, right, top perspective view of a LED panel showing our new design;

FIG. 2 is a rear, left, bottom perspective view thereof;

FIG. 3 is a front elevation view thereof;

FIG. 4 is a rear elevation view thereof;

FIG. 5 is a left side view thereof;

FIG. 6 is a right side view thereof;

FIG. 7 is a top view thereof;

FIG. 8 is a bottom view thereof;

FIG. 9 is a partially enlarged view thereof, illustrating a portion of the LED panel identified by reference numeral 9 in FIG. 1;

FIG. 10 is a partially enlarged view thereof, illustrating a portion of the LED panel identified by reference numeral 10 in FIG. 1;

FIG. 11 is a partially enlarged view thereof, illustrating a portion of the LED panel identified by reference numeral 11 in FIG. 2;

FIG. 12 is a partially enlarged view thereof, illustrating a portion of the LED panel identified by reference numeral 12 in FIG. 2;

FIG. 13 is a partially enlarged view thereof, illustrating a portion of the LED panel identified by reference numeral 13 in FIG. 2; and,

FIG. 14 is a partially enlarged view thereof, illustrating a portion of the LED panel identified by reference numeral 14 in FIG. 2.

The evenly-spaced broken lines show portions of the LED panel that form no part of the claimed design. The dash-dot-dot lines shown in FIGS. 1-2 and 9-14 encircling enlarged views are for annotative purposes only and form no part of the claim thereof.
